UNITED STATES PATENT OFFICE.

CHARLES R. SAATWEBER, OF NEW YORK, N. Y.

IMPROVEMENT IN LET-OFF MECHANISMS FOR LOOMS.

Specification forming part of Letters Patent No. 124,632, dated March 12, 1872.

To all whom it may concern:

Be it known that I, CHARLES RORERT SAATWEBER, of the city, county, and State of New York, have invented a new and useful Improvement in Let-Off Motion for Looms; and I do hereby declare this to be a full, clear, and exact description thereof, which will enable those skilled in the art to make and use the same, reference being had to the accompanying drawing forming part of this specification, in which drawing—

Figure 1 represents a side view of this invention. Fig. 2 is an end view of the same.

Similar letters indicate corresponding parts.

This invention consists in combining with the warp-beam or spool of a loom a double-armed lever, which connects at both ends with a friction-strap bearing on the warp-beam, and one arm of which is loaded with a weight in such a manner that, when the batten strikes up and the warp is drawn off from the warp-beam, the double-armed lever is caused to turn slightly on its pivot, and the slack in the friction-cord is in great measure prevented, the friction-strap not loosing its hold.

In the drawing, the letter A designates the warp-beam or warp-spool of a loom. In one of the end flanges of this beam is formed a groove, a, to receive a friction-strap, b, which is wound round said flange, and the ends of which are fastened to the opposite ends of a double-armed lever, B. This lever has its fulcrum on a pivot, c, and its long arm is loaded by a weight, d, which has a tendency to turn the warp-beam in the direction of the arrow marked thereon in Fig. 1, thereby exerting on the warp a tension proportionate to the weight and the distance of said weight from the fulcrum of the lever which supports the same.

I am well aware that single-armed levers

with weights and friction-straps have been applied to warp-beams, but the effect of my mechanism is different, as will be readily understood from the following explanation: If the lever B is single armed, the rear end b' of the friction-strap is secured to a fixed point; and when the batten strikes up, and the warp-beam is turned forward in the direction opposite to the arrow marked thereon in Fig. 1, said rear end of the friction-strap becomes slack, and the blow of the batten is liable to carry the warp-beam further than desirable by the loosening of the friction-strap, thereby producing a slack in the warp, which is detrimental to the work. If the warp-beam turns in the direction of the arrow, the lever B swings on its pivot, and the slack which would be produced in the rear end b' of the friction-strap is partially taken up by the downward motion of the short arm of the lever B, and the danger of carrying the warp-beam too far, and of producing a slack in the warp, is materially lessened by the friction-strap being held taut, and thus prevented from slipping.

This let-off mechanism I employ with advantage on warp-beams situated beneath the chain; but in looms for weaving corsets or other irregular goods, I have found it convenient to place a portion of the warp-beams or spools beneath, and another portion above the chain.

What I claim as new, and desire to secure by Letters Patent, is—

The double-armed lever B, in combination with the friction-strap b' and warp-beam or spool A, all arranged and operating substantially as shown and described.

CHARLES ROBERT SAATWEBER.
